STRIP DISPENSING APPARATUS

John Q. Sherman and Albert W. Metzner, Dayton,
Ohio; said Metzner assignor to said Sherman

Application June 4, 1934, Serial No. 720,084

43 Claims. (Cl. 262—12)

This invention relates to manifolding apparatus and more particularly to automatic aligning and registering means for manifolding registers and strip feeding attachment for writing machines.

For purpose of illustration, the invention is herein shown and described as embodied in a portable register or holder for a packet of continuous series connected detachable printed forms folded into zigzag formation and issued in superposed registering relation with portions of transfer material interleaved therebetween, ready to receive written inscriptions. As indicative of the wide range of application of the invention, the aligning and registering means is also shown embodied in a carbon shifter attachment for a writing machine over which superposed printed forms are progressively advanced from a source of supply to the platen roll of the writing machine. It will be obvious that the invention is not limited to either of these embodiments but may be incorporated in other forms of manifolding apparatus or may be used, if desired, with single record strips for temporarily arresting the advancement thereof when predetermined lengths have been withdrawn from the supply container and so serve to locate the dispensed portions of the strip in a predetermined position relative to a writing tablet.

The object of the invention is to improve the construction as well as the means and mode of operation of manifolding registers and other strip dispensing apparatus whereby they will not only be simple in construction and capable of being economically manufactured, but will be more efficient in use, capable of rapid operation, accurate in action, and unlikely to get out of repair.

A further object of the invention is to provide automatic aligning and registering means for strips whereby accurate relation of the strips in writing position may be assured.

A further object of the invention is to provide means for temporarily retarding the advancement of the record forms when a predetermined length has been withdrawn from a supply container or holder, and to automatically release the forms preparatory to further advancement under influence of increased pulling tension upon the forms.

A further object of the invention is to afford an appreciable signal to the operator when the forms have been advanced a predetermined distance.

A further object of the invention is the em-

bodiment of simple but efficient strip aligning and registering means in a container or dispensing apparatus of small compact form.

A further object of the invention is the application of improved aligning and registering means to strip feeding and carbon shifter attachments for writing machines.

A further object of the invention is to provide a strip dispensing apparatus having the desirable features and advantageous characteristics hereinafter mentioned.

With the above primary and other incidental objects in view, as will more fully appear in the specification, the invention consists of the features of construction, the parts and combinations thereof, and the mode of operation, or their equivalents, as hereinafter described and set forth in the claims.

In the drawings wherein is shown the preferred but obviously not necessarily the only forms of the embodiment of the invention, Fig. 1 is a perspective view of a portable manifolding register or strip dispensing apparatus embodying the present invention, the register or container being empty. Fig. 2 is a longitudinal sectional view of a portable manifolding register or dispensing device with a packet of zigzag folded forms contained therein showing the folds of the forms engaged by the aligning and registering device, whereby the terminal forms are positioned to receive the written inscription. Fig. 3 is a similar view, showing the relation of the parts and the relative position of the forms during the period of advancement. Fig. 4 is a perspective view of a sheet of transfer material for use in the register or dispensing apparatus. Fig. 5 is a perspective view of the apparatus loaded with a packet of manifolding material, the register being open to show the relative disposition of succeeding portions of the continuous strips of manifolding forms. This view also illustrates a slight modification of the spring actuator for the aligning plate. Fig. 6 is a fragmentary longitudinal sectional view, showing a duplex register from which record strips are adapted to be fed from opposite sides of the container or holder. Fig. 7 is a detail perspective sectional view. Fig. 8 is a side elevation of a strip dispensing apparatus and carbon shifter for a writing machine, such as forms the subject matter of co-pending application Serial No. 703,694, filed December 23, 1933 to which the present aligning and registering device has been applied.

Like parts are indicated by similar characters of reference throughout the several views.

Referring to the drawings, 1 is a box-like container for a packet 2 of superposed strips of series connected forms reversely folded collectively into zigzag formation and provided with transverse 5 weakening lines 3 coincident with the successive folds upon which succeeding portions or forms may be detached from the supply strips. The container 1 is provided with a hinged cover 4 which affords a writing tablet over which with- 10 drawn portions of the strips may be reversely folded into writing position and their free ends removably engaged beneath a spring finger or clip 5. The cover or writing tablet 4 is swingingly connected to the box or container 1 upon a 15 transverse rod 6 extending transversely of the container and interiorly thereof. Pivotaly mounted within the container or box 1 is a swing- 20 ing frame comprising side plates 7—7 and a trans- 25 verse pallet or plate 8. The forward edge of this plate 8 is curled upon itself to form a rounded 30 bead or relatively blunt margin which under cer- 35 tain conditions forms a guide about which the rec- 40 ord strips are drawn. The rearward portion of 45 this transverse plate or pallet 8 is depressed at 50 9 forming a channel-like extension.

Slidingly mounted upon the transverse plate or pallet 8 for fore and aft reciprocation is a 55 second guide plate 10 suitably connected with the pallet or plate 8 for limited to and fro motion, the 60 forward edge of which is relatively sharp and nor- 65 mally projects beyond the rounded edge of the pallet or plate 8 and beyond the transverse rod 6 which forms the mounting for the writing tablet 4. This sliding guide plate 10 is yieldingly 70 urged into such advanced position wherein it 75 protrudes beyond the rounded edge of the guide plate or pallet 8 by a suitable spring 11 extending about mounting studs 12 within the depressed portion 9 of the pallet or plate 8 and engaging 80 ears or fingers 13 projecting from the rear mar- 85 gin of such sliding guide plate 10 into the said depression 9. The spring 11 normally holds the movable guide plate 10 in its advanced position but enables such plate to be retracted against 90 the tension of the spring 11 to a position flush with or slightly beyond the rounded edge of the guide plate 8.

In lieu of the actuating spring 11 engageable 95 with the dependent ears or fingers 13 upon the plate 10, such reciprocatory guide plate 10 may be formed with rearwardly extending arms 14 disposed in suitable guides outside the side plates 7 of the swinging frame and helical retracting 100 springs 15 may be connected at one end to the rearwardly extending arms 14 and at their op- 105 posite ends to the swinging frame for the pur- 110 pose of retracting the reciprocatory guide plate 10 and projecting it beyond the rounded blunt margin of the secondary guide plate 8. Such 115 construction is clearly illustrated in Figs. 5 and 6.

The side plates 7 are formed with marginal 120 notches 16 which are preferably slightly under- 125 cut to receive a transverse supporting strip 17 of a sheet of transfer material 18, illustrated par- 130 ticularly in Fig. 4, which is to be disposed between the terminal portions of the superposed record strips comprising the packet 2 as is shown in Figs. 135 2 and 5. The transfer sheet 18 is anchored within the container or box 1 by the engagement of 140 the ends of the strip 17 within the marginal notches 16 of the swinging frame. Such ends of the supporting strip 17 project laterally be- 145 yond the margins of the transfer sheet 18 and beyond those of the record strips comprising the 150 packet 2.

There may be any suitable number of such transfer sheets 18 anchored within the notches 16 of the swinging frame in accordance with the number of manifoldeed copies to be produced.

The marginal edge of the guide plate 10 when 155 in extended position is spaced from the marginal edge of the cover or writing tablet at the opposite end of the container or box 1 a distance equal to the spacing of successive reverse folds 160 of the zigzag manifolding assembly.

The terminal portions of the superposed record strips withdrawn from the packet are folded collectively reversely about the guide plates 8 and 165 10 as shown particularly in Figs. 2 and 3. The reversely folded portions of the strips are then interleaved with the transfer sheets 18 in such 170 relation that one strip of the assembly extends beneath and another strip over each of the mounting strips 17 and attached transfer sheets 18, and the interleaved portions of the record 180 strips together with the intervening sheets of 185 transfer material are then again reversely folded over the marginal edge of the cover or writing tablet 4. Such finally folded portions and the interleaved transfer material lying upon the top 190 of the cover or writing tablet are secured at their 195 free ends by being tucked beneath the clasp or 200 clamping finger 5, or hooked over projections or 205 studs, such as shown at 20 in Fig. 6, by use of 210 file holes in the forms as shown in Fig. 5, as 20a. 215 In such adjusted relation of the record strips, 220 the rearmost marginal edge of the cover or writing tablet 4 fits snugly within one fold of the 225 zigzag manifolding assembly while the next suc- 230 ceeding fold thereof conforms closely to the edge 235 of the guide plate 10 which engages within such 240 folds. The engagement of the guide plate 10 245 within one of these folds of the strips insures 250 close conformity of the other folds about the edge 255 of the writing tablet and therefore accurately 260 locates the withdrawn portions of the strips in regis- 265 try and alignment with each other in writing 270 position upon the top of the cover or writing tab- 275 let 4.

After the initial forms, overlying the top of 280 the holder or dispensing device have been in- 285 scribed and it is desired to advance the succeed- 290 ing set of forms into writing position, the in- 295 scribed forms are disengaged from the clasp or 300 holding means and are unfolded into an extended 305 position rearwardly away from the holder or 310 container, and upon pulling tension being applied 315 thereto to withdraw additional portions of the 320 strips from the box or container 1, the prevention 325 by the folds of the sliding movement of the forms 330 about the edge of the guide plate 10 will cause 335 such plate to be retracted against the yielding 340 resistance of its spring 11 or 15 as the case may 345 be until the engaging margin of such plate 10 350 is substantially flush with the rounded blunt 355 margin of the secondary guide plate 8 with which 360 the strips then engage and which acts as a strip- 365 per for disengaging the fold of the strip from 370 the edge of the plate 10 thereby allowing the strip 375 to advance more easily. As the fold passes 380 beyond the margin of the plate 10 from which 385 it is disengaged by the rounded blunt edge of 390 the plate 8 when the retarding plate 10 is re- 395 tracted, the pulling tension upon the plate 10 400 being thereby relieved, such plate will return 405 automatically to its advanced position ready for 410 reengagement with the next succeeding fold of 415 the strips, which in the meantime being looped at 420 such point flow easily about the edge of the plate 425 until the fold is encountered thereby. The en- 430 75

gagement of the plate with the fold imposes sufficient resistance to the movement of the strips to indicate to the operator that a full length of form has been withdrawn.

5 During such advancement of the record strips, the transfer sheets 18 have been held stationary while the strips have advanced relative thereto until the previously inscribed forms are extended beyond the ends of the transfer sheets 18. The 10 inscribed forms may then be torn off. The leading edge of the succeeding set of forms, having the transfer sheets 18 interleaved therebetween and reversely folded over the top of the writing tablet 4, may now be advanced under the clamp 15 5 to be clamped in place during the next writing operation.

To provide a suitable exit opening beneath the top or writing tablet 4 and to facilitate the withdrawal of record strips therethrough the edge 20 of the box or container 1 is bent slightly outwardly to form a lip 19.

If desired, the box or container 1 may be made of sufficient depth to contain two packets of folded record strips comprising forms of different 25 character which may be fed in the manner before described from either side of the register. That is to say, both the top and bottom of the box or container may comprise writing tablets and the arresting and aligning means heretofore 30 described may be provided in duplicate within the box or container whereby a different set of forms may be dispensed from each side of the register. In such case, projections or feet 20 are preferably provided upon which the register 35 35 may be supported in slightly elevated position so that the pressure or weight of the register will not be likely to cause offsetting of the carbon or transfer material upon the underlying record strips.

40 As illustrative of the application of the invention to other forms of strip feeding mechanism or duplicating apparatus, there has been shown in Fig. 8 a carbon shifter apparatus to be mounted upon a writing machine consisting of an upwardly and rearwardly extending frame 21, over which superposed record strips are fed from a supply packet 23 to the platen roll 24 of the writing machine. Mounted upon the frame 21 are suitable strip guiding devices and a reciprocatory 45 50 carbon carrier which, per se, form no part of the present invention but which are fully shown and described in companion application Serial No. 703,694, to which reference is made.

At the top of the frame 21 there is provided a 55 stationary plate 25 corresponding to the pallet or plate 8 of the register construction before described. This plate 25 has a rounded margin 26 and is depressed or offset at 27 to form a channel-like recess to receive the actuating 60 spring. Slidingly mounted upon the plate 25 is a reciprocatory plate 28 corresponding to the plate 10 before described, urged into advance position by a spring 29 within the recess 27 and corresponding to the spring 11 of the register 65 construction. This arresting and aligning device mounted at the top of the carbon shifter frame 21 is substantially identical with and operates in the same manner as that embodied in the portable register and is in fact substantially a 70 duplication thereof applied to the carbon shifter apparatus.

The strip engaging edge of the guide and arresting member 10 being spaced from the opposite edge of the writing tablet 4 the distance 75 of one form length insures that the fold of the

strip engageable with the edge of the writing tablet shall conform closely thereto. If the fold of the strip is displaced away from the edge of the writing tablet 4 or drawn slightly therebeyond, such displacement necessarily tends to retract the guide member 10 against the resistance of its spring 11 and thereby imposes a tension upon the strip in reverse direction sufficient to draw the first fold of the strip into close conformity with the edge of the writing tablet and thereafter hold it in such relation so that accurate registry and alignment is insured. 5

If desired, the guide and arresting member 10 may be normally spaced slightly more than one form length from the fold engaging edge of the writing tablet whereby such guide and arresting member is slightly retracted against spring tension while engaged with the fold of the strip, to impose thereon a tension in reverse direction sufficient to maintain both the folds in close conformity with the respective fold engaging edges, without, however, causing sufficient strain to disengage the fold from either engagement. 10 20

Cross reference is made to copending companion applications, Serial No. 673,207, filed May 27, 1933, Serial No. 677,629, filed June 26, 1933, Serial No. 741,578, filed August 27, 1934, Serial No. 741,579, filed August 27, 1934, and Serial No. 741,580, filed August 27, 1934. 25

From the above description it will be apparent 30 that there is thus provided a device of the character described possessing the particular features of advantage before enumerated as desirable, but which obviously is susceptible of modification in its form, proportions, detail construction and arrangement of parts without departing from the principle involved or sacrificing any of its advantages. 35

While in order to comply with the statute, the invention has been described in language more 40 or less specific as to structural features, it is to be understood that the invention is not limited to the specific features shown, but that the means and construction herein disclosed comprise the preferred form of several modes of putting the 45 invention into effect, and the invention is therefore claimed in any of its forms or modifications within the legitimate and valid scope of the appended claims.

Having thus described our invention, we claim: 50

1. In a strip dispensing apparatus, a container 55 for a packet of continuous series connected detachable record forms folded into zig-zag formation, and a writing tablet over which successive forms withdrawn from the container may be disposed to receive written inscriptions thereon, a guide means within the container around which the forms are drawn in their passage from the container to the writing tablet, said guide means including a stationary member and a superposed movable member the edge of which normally projects beyond the stationary member for engagement in successive folds of the zig-zag forms to yieldingly arrest the movement of the forms when a predetermined length has been withdrawn and normally holding the strips out of engagement with the stationary member, and a spring against the tension of which the movable member is retractable relative to the stationary member by the pulling strain upon the forms thereby permitting engagement of the strips with the stationary member to effect dislodgment of the fold of the forms from said movable member. 60 65 70

2. In a strip dispensing apparatus, a container 75

for a packet of continuous series connected detachable forms folded into zig-zag formation, and a writing tablet over which successive forms withdrawn from the container may be disposed
 5 to receive thereon written inscriptions, a relatively sharp edged guide member within the container about which the forms are drawn in their passage from the packet onto the writing tablet and engageable in successive folds of the zig-zag
 10 forms to temporarily arrest the withdrawal thereof, said engaging member being movable under pulling influence of the forms being withdrawn and a stripper member for disengaging the fold of the forms from the guide member upon retraction thereof.

3. In a strip dispensing apparatus, a container for a packet of continuous series connected detachable forms, and a writing tablet over which successive forms withdrawn from the container
 20 may be disposed to receive written inscriptions thereon, and a pair of parallel relatively offset superposed guide members for the forms located within the container and alternately engaged by the strips, one of which is engageable in succeeding folds of the zig-zag forms in their passage from the packet to the writing tablet to temporarily arrest the withdrawal movement thereof, the other of which is engageable with the forms in offset relation with the folds thereof, one of
 25 said guide members being movable relative to the other guide under pulling influence of the forms, thereby alternating the engagement of the forms with the respective guide members to automatically disengage a fold of the forms from the engaging guide member.

4. In a strip dispensing apparatus, a container for a packet of continuous series connected detachable forms, and a writing tablet over which successive forms withdrawn from the container
 40 may be disposed to receive written inscriptions thereon, and a pair of parallel relatively offset superposed guide members for the forms located within the container, one of which is engageable in succeeding folds of the zig-zag forms in their
 45 passage from the packet to the writing tablet to temporarily arrest the withdrawal movement thereof, the other of which is engageable with the forms in offset relation with the folds thereof, the engagement of the forms with the respective
 50 guide members being automatically reversible under influence of the pulling tension of the forms to effect disengagement of a fold of the forms from the fold engaging guide member.

5. In a strip dispensing apparatus, a container for a packet of continuous series connected detachable forms, and a writing tablet over which successive forms withdrawn from the container may be disposed to receive written inscriptions thereon, and a pair of parallel relatively offset
 60 superposed guide members for the forms located within the container and relatively adjustable under pulling tension upon the forms, one of which is engageable in succeeding folds of the zigzag forms in their passage from the packet to
 65 the writing tablet to temporarily arrest the withdrawal movement thereof, the other of which is engageable with the forms in offset relation with the engaged fold thereof upon relative adjustment of said guide members to automatically effect
 70 dislodgment of the fold of the forms from the engaging guide member.

6. In a strip dispensing apparatus, a container or a packet of continuous series connected detachable forms, and a writing tablet over which successive forms withdrawn from the container may
 75

be disposed to receive written inscriptions thereon, a pair of substantially parallel guide members located within the container alternately engaged by successive forms in their passage from the packet to the writing tablet, one of said guide members being supported upon and movable relative to the other under influence of the pulling tension for the forms to alternate the engagement of the forms therewith, one of said guide members being adapted for engagement in succeeding folds of the zigzag forms to temporarily arrest the movement of the forms, the other guide member being non-arresting in character and adapted by its engagement with the forms to automatically effect the disengagement of an engaged fold from the arresting guide member, preparatory to further advance movement of the forms.

7. A strip dispensing apparatus wherein continuous series connected detachable forms initially folded into zig-zag formation are progressively advanced from a source of supply to a writing position, including a retractable guide member having a relatively sharp edge about which the forms are reversely drawn and adapted to engage in succeeding folds of the zig-zag forms to temporarily arrest the movement of the forms when predetermined lengths thereof have been advanced, a spring against the yielding tension of which the guide member is retractable under influence of pulling tension upon the forms to automatically release the engaged fold, and a relatively stationary member with which the forms engage within the folded portion thereof upon retraction of said movable guide member to thereby dislodge the engaged fold of the forms from the retractable guide member.

8. A strip dispensing apparatus wherein continuous series connected detachable forms, initially folded into zig-zag formation, are progressively advanced from a source of supply to a writing position, including a movable member having an edge about which the forms are reversely drawn and adapted to engage in succeeding folds of the zig-zag forms to temporarily arrest the movement of the forms when predetermined lengths thereof have been advanced, and a stationary non-arresting guide member disposed in parallel offset relation with the form arresting edge and also engageable within the fold of the forms, relative to which the said edged member is movable under influence of pulling strain upon the forms to automatically effect dislodgement of the engaged fold of the forms from the arresting edge.

9. In a strip dispensing apparatus for a packet of continuous series connected detachable forms folded into zigzag formation, a fixed relatively blunt member and a movable member having a relatively sharp edge about which the forms are reversely drawn in their travel from a source of supply to a writing position, and retractable by pulling tension upon the forms, the edge of said retractable member being adapted to engage in successive folds of the zigzag forms to temporarily arrest the advancement thereof, the relatively blunt member being engageable within the same fold upon retraction of the edged member to automatically dislodge the engaged fold from the form arresting edge upon relative movement of said movable member, said movable member being actuated by pulling tension upon the forms.

10. In a strip dispensing apparatus for a packet of series connected detachable forms folded into zigzag formation, a container for the packet, a

- writing tablet over which withdrawn forms may be reversely folded into writing position, an edge portion in transverse relation with the path of travel of the forms with which the forms are engageable and about which the forms are reversely drawn from the packet to writing position upon the tablet, and engageable in successive folds of the forms to temporarily arrest the advancement of the forms when predetermined portions thereof have been withdrawn, and a guide member reversely disposed in spaced relation with the form engaging edge of the writing tablet about which the forms are also reversely drawn in their travel from the packet to the writing position, said guide member being engageable in the next succeeding fold of the forms simultaneously with the engagement of the edge of the writing tablet in a fold thereof, and tension means for said guide by which the guide is caused to exert a pulling tension on the forms to draw a fold of the forms into close engagement with the said edge of the writing tablet.
11. In a strip dispensing apparatus for a packet of continuous series connected detachable forms folded into zig-zag formation two substantially parallel guide members disposed transversely of the path of travel of the forms and about which the forms are reversely drawn from the packet to a writing position, one of said guide members having engagement with successive folds of the zig-zag forms to temporarily arrest the advancement of the forms when predetermined lengths thereof have been withdrawn, the other guide member being effective to automatically dislodge the engaged fold from the arresting guide preparatory to further advancement of the forms, said guide members being alternately engageable with the forms under influence of pulling tension on the forms.
12. In a strip dispensing apparatus, a container for a packet of continuous series connected detachable forms folded into zig-zag formation, a writing tablet over which withdrawn forms may be reversely folded into writing position, a swinging U-shaped frame within the container the transverse portion of which overlies the packet and about which the forms are reversely drawn in their advancement from the packet to writing position, a leaf slidable on said transverse portion to a position with its margin projecting therebeyond for engagement with a fold of the zig-zag forms to temporarily arrest the advancement thereof, a spring against the tension of which the leaf is retractable under influence of pulling tension upon the forms and stripper means operative upon retraction of said leaf to effect automatic dislodgment of the engaged form preparatory to further advancement of the forms.
13. In a strip dispensing apparatus, a container for a packet of continuous series connected detachable forms folded into zig-zag formation, a container for the packet, a writing tablet over which withdrawn forms may be reversely folded into writing position, guide means within the container about which the forms are reversely drawn in their advancement from the packet to writing position, said guide means being engageable within a fold of the zig-zag forms to temporarily arrest the advancement thereof, and means also engageable in the same fold of the forms for effecting dislodgment of the fold of the forms from the arresting guide by influence of pulling tension on the forms.
14. A record strip dispensing apparatus where-
- in a zigzag folded strip of record material is advanced through a definite path of travel from a source of supply to a writing position, characterized by a member having an edge engageable in succeeding folds of the strip to temporarily arrest the advancement of the strip, a stripper member engageable in the same fold of the strip to dislodge the fold from the arresting edge, and spring means yieldingly urging one of said members into engagement with the strip placed under tension by pulling tension upon the strip to enable dislodging engagement of the strip of material and the stripper member.
15. A record strip dispensing apparatus where-
in a zigzag folded strip of record material is ad-
vanced through a definite path of travel from a
source of supply to a writing position, character-
ized by a member having an edge engageable in
succeeding folds of the strip to temporarily ar-
rest the advancement of the strip, a stationary
stripper member located in proximate relation
thereto, said strip arresting member being mov-
able past the stationary stripper member under
influence of pulling tension upon the strip to
effect automatic dislodgement of the engaged fold
from the strip arresting member.
16. A record strip dispensing apparatus where-
in a zigzag folded strip of material is fed through
a definite path of travel from a source of supply
to a writing position, characterized by a pair of
relatively movable superposed members one of
which has a relatively sharp edge for engage-
ment in a fold of the strip to temporarily arrest
the advancement of the strip, the other of which
has a relatively blunt strip engaging surface in-
termittently engageable with the strip for effect-
ing dislodgment of the strip from said fold en-
gaging member, and spring tension means against
which one of the members is movable relative to
the other by pulling tension upon the strip to
effect automatic release of the engaged fold of
the strip.
17. A record strip dispensing apparatus where-
in a zigzag folded strip of material is fed through
a definite path of travel from a source of supply
to a writing position, characterized by a reciproca-
tory member and a stationary member past which
the strip travels in its advance movement, both
of said members being simultaneously engageable
in successive reverse folds of the strip to tempo-
rarily hold the advanced portion of the strip in
writing position, and spring tension means against
which the reciprocating member is movable by
pulling tension on the strip to automatically draw
the other engaged fold into close conformity with
the stationary member.
18. A strip dispensing apparatus wherein a
strip of record material folded into zigzag forma-
tion is advanced from a source of supply to a
writing position through a prescribed path of
travel wherein it abruptly reverses its direction
of travel, characterized by two reversely disposed
relatively movable edged members, the edges of
which are simultaneously engageable in succeed-
ing reverse folds of the strip to locate an ad-
vanced portion of the strip in writing position, and
spring tension means tending to further separate
the edged member to subject the strip to tension
therebetween by which the folds are more closely
seated upon the engaging edges of said members.
19. A strip dispensing apparatus wherein a strip
of record material folded into zigzag formation
is advanced from a source of supply to a writing
position through a prescribed path of travel
wherein its direction of extent is abruptly re-

versed, including relatively spaced guide members about each of which the strip extends in reverse directions and simultaneously engageable in succeeding folds thereof to locate an advanced position of the strip in writing position, one of said guide members being yieldable in relation to the other.

20. A strip dispensing apparatus wherein a strip of record material folded into zigzag formation is advanced from a source of supply to a writing position through a prescribed path of travel wherein its direction of extent is abruptly reversed, including a member about which the strip is reversely folded and engageable in the fold thereof, and a spring tensioned engaging member engageable with the next succeeding fold of the strip and exerting retractive influence thereon for tensioning the strip in reverse direction to maintain the engaged fold of the strip in close conformity with the fold engaging member.

21. A strip dispensing apparatus wherein a strip of record material folded into zigzag formation is advanced from a source of supply to a writing position through a prescribed path of travel wherein its direction of extent is abruptly reversed, including a writing tablet about the margin of which the strip is reversely folded into writing position thereon, and a spring tensioned member engageable with the next succeeding fold of the strip to maintain the first fold thereof in close conformity with the edge of the writing tablet.

22. A strip dispensing apparatus wherein a strip of record material, folded into zigzag formation is intermittently advanced from a source of supply to a writing position and temporarily held in each advance position thereof, including a swinging frame, a movable strip engaging member carried thereby and movable independently thereof adapted by its movement independently of the swinging motion of the frame to release the strip for further advance movement, said strip engaging member being automatically movable to release the strip for further advance movement under influence of pulling tension upon the strip.

23. A strip dispensing apparatus wherein superposed record strips apertured at spaced intervals and reversely folded into zigzag formation are progressively advanced from a source of supply into a writing position and temporarily arrested in predetermined positions of adjustment, a receptacle for a packet of such folded strips from which the strips are to be withdrawn, a writing tablet about the edge of which the withdrawn portions of the strips are to be reversely folded coincident with a preformed fold thereof into writing position upon the writing tablet, a detent means automatically engageable with the strips to temporarily retard the advancement of the strips when a predetermined length thereof has been advanced, a swinging frame upon which the detent means is mounted for shifting movement into and out of engagement with the strips independently of the swinging movement of the frame, the engaged strips being automatically disengageable from said detent under increased pulling tension upon the strips preparatory to further advancement thereof.

24. In a strip dispensing apparatus for a packet of continuous series connected detachable forms folded into zigzag formation, a fixed guide and a movable guide simultaneously engageable in succeeding folds of the forms about which the forms are reversely drawn in their travel from a

source of supply to a writing position, the movable guide being adapted to engage in successive folds of the zigzag forms to temporarily arrest the advancement thereof, and stripper means effective to automatically dislodge the engaged fold from the movable form arresting guide upon relative movement of said movable guide, said movable guide being actuated by pulling tension upon the forms.

25. A record strip dispensing apparatus where- 10 in a zigzag folded strip of record material is advanced through a definite path of travel from a source of supply to a writing position, characterized by two members having reversely disposed relatively adjustable edges simultaneously engageable in succeeding folds of the strip to temporarily hold advanced portions of the strip in writing position, one of said strip engaging members being movable to effect disengagement of the engaged fold therefrom under excessive pulling tension 20 on the record material strip.

26. A strip dispensing apparatus wherein a strip of record material folded into zigzag formation is advanced from a source of supply to a writing position through a prescribed path of 25 travel wherein its direction of extent is twice abruptly reversed, including a writing tablet about the margin of which the strip is reversely folded into writing position thereon with a fold of which the edge of the top engages, and a spring tension member in the opposite end of the apparatus engageable with the next succeeding fold of the strip to provide means for registering simultaneously at two points in the strip of record material.

27. A strip dispensing apparatus wherein a strip of record material folded into zigzag formation is advanced from a source of supply to a writing position through a prescribed path of travel wherein its direction of extent is twice 40 abruptly reversed, including a top about the margin of which the strip is reversely folded into writing position thereon, the edge of which engages in a fold of the strip and a spring tension member in the opposite end of the apparatus engageable with the next succeeding fold of the strip, said top margin and said spring tension member constituting aligning devices for aligning simultaneously at successive points of the record material strip.

28. A strip dispensing apparatus wherein a strip of record material folded into zigzag formation is advanced from a source of supply to a writing position through a prescribed path of travel wherein its direction of extent is twice 55 abruptly reversed, including a writing tablet about the margin of which the strip is reversely folded into writing position thereon, the edge of which is engageable in a fold thereof, and a spring tensioned member in the opposite end of the apparatus engageable with the next succeeding fold of the strip, said writing tablet margin and said spring tension member constituting aligning devices for aligning simultaneously at successive points of the record material strip, and pins at one end of the writing tablet over which the forms may be held in writing position.

29. Apparatus of the character described having in combination a movably mounted strip aligner around which the strips are adapted to 70 fold and a stripping device stationarily mounted adjacent to the strip aligner engageable within the bight of the folded strip and effective to cause dislodgment of the strips from said aligner upon retractive movement of the latter and tension 75

means against the yielding resistance of which the aligner is automatically retractable under influence of advance pulling tension upon the strip to automatically release the strip for advance movement.

5 30. Apparatus of the character described having in combination a reciprocatory detent plate engageable in succeeding folds of a folded strip drawn thereabout and a stationary stripper member located adjacent thereto within the same fold of the strip, past which the engaging edge of the detent plate is withdrawn upon retraction thereof to dislodge the strip from the detent plate and tension means against the yielding resistance 10 of which the detent plate is automatically retractable under influence of advance pulling tension upon the strip to automatically release the strip for further advance movement.

10 31. Apparatus of the character described, having in combination a reciprocatory strip aligner around which the strips are adapted to fold, and a stripper device stationarily mounted adjacent to the strip aligner and engageable within the engaged bight of the strip upon retraction of the 15 aligner to cause disengagement of folds of the strips from the aligner upon movement of the latter and tension means against the yielding resistance of which the aligner is automatically retractable under influence of advance pulling tension 20 upon the strip to automatically release the strip for advance movement.

25 32. In a strip dispensing device, a container for a packet of continuous series connected detachable forms folded into a zigzag formation including a writing tablet over which withdrawn forms may be reversely folded into writing position thereon, an edge of which is engageable in a fold of the forms to position the forms relative to the writing position, and a strip tensioning device engageable with the next succeeding 30 folds of the forms and exerting retractive influence thereon to draw the first mentioned fold into close conformity with the edge of the writing tablet.

35 33. In a strip dispensing apparatus, a container for a packet of continuous series connected detachable forms folded in zigzag formation from which the forms are progressively withdrawn into writing position on top of the container, including two relatively spaced relatively adjustable guide portions about which the forms are reversely drawn first in one direction and then in the other, and simultaneously engageable in succeeding folds of the forms and tension 40 means tending to separate the guide members and thereby exerting pulling influence upon the forms by which the engaged folds thereof are drawn into close conformity with the respective guide portions.

45 34. A manifolding register including a container for a supply packet of reversely folded superposed record strips, having an exit opening through which succeeding portions of the strips may be withdrawn, a cover therefor forming a writing tablet over which withdrawn portions of the strips may be disposed in writing position, with the edge of which the initial fold of the strips coincides when the withdrawn portions are in writing position, and strip tensioning 50 means having engagement with the strips within the container and exerting retractive influence thereon to draw said fold into conformity with the edge of the writing tablet.

55 35. A manifolding register including a container for a packet of continuous series-con-

nected forms reversely folded into zig-zag formation, a writing tablet over which succeeding forms withdrawn from the container may be disposed in writing position, form engaging means associated with the writing tablet for holding the 5 advance end of a form when in writing position, and strip tensioning means engageable in a fold of the reversely folded series connected forms for exerting retractive influence upon the forms to maintain the adjusted form tight upon the 10 writing tablet.

15 36. A manifolding register including a container for a packet of continuous series-connected forms reversely folded into zig-zag formation, a writing tablet over which succeeding forms withdrawn from the container may be disposed in writing position, form engaging means associated with the writing tablet for holding the advance end of a form when in writing 20 position, and a spring actuated plate engageable in succeeding folds of the series-connected reversely folded forms as the forms are advanced from the container to the writing position and exerting retractive tension thereon in opposition to the form engaging means engaged 25 with the advance end of the positioned form.

30 37. In a strip dispensing apparatus wherein a strip of record material folded into zig-zag formation is advanced from a source of supply to a writing position through a path of travel wherein its directional extension is abruptly reversed, including a writing tablet about the edge of which the strip is to be folded in reverse direction into writing position thereon, a swinging frame, a strip engaging member carried thereby, 35 said member having a relatively sharp edge engageable in a succeeding fold of the strip, and means tending to move said strip engaging member to tension the first mentioned fold about the writing tablet edge.

35 38. In a strip dispensing apparatus wherein a strip of record material folded into zig-zag formation is advanced from a source of supply to a writing position through a path of travel wherein its directional extension is abruptly reversed, 40 including a writing tablet about the edge of which the strip is to be folded in reverse direction into writing position thereon, a swinging frame, a strip engaging member carried thereby, said member having a relatively sharp edge engageable in a succeeding fold of the strip to maintain the first fold in close conformity with the edge of the writing tablet, said strip engaging member being spaced from said writing tablet edge a 45 distance equal to the length of a strip of record material between two succeeding folds when in operative position.

50 39. In a strip dispensing apparatus wherein a strip of record material folded into zig-zag formation is advanced from a source of supply to a writing position through a path of travel wherein its directional extension is abruptly reversed, including a writing tablet about the edge of which the strip is abruptly turned and which is engageable in a fold thereof to locate a congruous withdrawn portion of the strip in writing position upon the cover, a swinging frame, a strip engaging member carried thereby, said member having a relatively sharp edge engageable in a succeeding fold of the strip to maintain the first fold in 55 close conformity with the edge of the writing tablet.

60 40. In a strip dispensing apparatus, wherein a strip of record material folded in zig-zag formation is advanced from a source of supply to a 65

- writing position through a path of travel wherein its directional extension is abruptly reversed, including a writing tablet about the edge of which the strip is abruptly turned and which is engageable in a fold thereof to locate a congruous portion of the strip in writing position on the cover, and a strip engaging member having a relatively sharp edge engageable in a succeeding fold of the strip to maintain the first fold in close conformity with the edge of the writing tablet.
41. In a strip dispensing apparatus wherein a strip of record material folded in zig-zag formation is advanced from a source of supply to a writing position through a path of travel wherein its directional extension is abruptly reversed, including a writing tablet about the edge of which the strip is abruptly turned and which is engageable in a fold thereof to locate a congruous portion of the strip in writing position on the cover, and a strip engaging member having a relatively sharp edge engageable in a succeeding fold of the strip, and means tending to move said strip engaging member to maintain the first fold in close conformity with the edge of the writing tablet.
42. In a strip dispensing apparatus wherein a strip of record material folded in zig-zag formation is advanced from a source of supply to a writing position through a path of travel wherein

its directional extension is abruptly reversed, including a writing tablet about the edge of which the strip is abruptly turned and which is engageable in a fold thereof to locate a congruous portion of the strip in writing position on the cover, and a strip engaging member having a relatively sharp edge engageable in a succeeding fold of the strip, and means tending to move said strip engaging member to maintain the first fold in close conformity with the edge of the writing tablet, 10 said strip engaging member being spaced from said writing tablet edge a distance equal to the length of a strip of record material between two succeeding folds when in operative position.

43. A manifolding register including a container for a supply packet of reversely folded superposed record strips having an exit opening through which succeeding portions of the strips may be withdrawn, a cover therefor forming a writing tablet over which withdrawn portions of the strips may be drawn into writing position, a reciprocatory detent plate engageable in succeeding folds of the strips to temporarily retard their movement and a swinging carrier therefor mounted in the container and underlying the writing tablet.

JOHN Q. SHERMAN,
ALBERT W. METZNER.
